UNITED STATES PATENT OFFICE.

ARTHUR A. BOOTH, OF SPOKANE, WASHINGTON.

EXCAVATOR.

No. 806,770.

Specification of Letters Patent.

Patented Dec. 12, 1905.

Application filed June 6, 1905. Serial No. 263,941.

To all whom it may concern:

Be it known that I, ARTHUR A. BOOTH, a citizen of the United States, residing at Spokane, in the county of Spokane and State of Washington, have invented new and useful Improvements in Excavators, of which the following is a specification.

My invention pertains to excavators; and it has for one of its objects to provide an excavator embodying a shovel and a conveyer so constructed and connected with a main frame that they can be expeditiously adjusted in a lateral direction on the main frame with the expenditure of but little effort on the part of the attendant.

Another object of the invention is the provision in an excavator of a shovel, a conveyer, and means under the control of an attendant for instantaneously raising the shovel and conveyer in the event of the former encountering a stump or other obstruction.

Another object is the provision in an excavator of a shovel so connected to a carrier that when the shovel brings up against a fixed obstruction the connection will be broken and the shovel will be permitted to move rearwardly and the carrier enabled to ride over the obstruction, thereby avoiding wrecking of the machine.

Another object is the provision in an excavator of a transverse conveyer which is adapted to be adjusted vertically and also in the direction of its length and adjustably fixed to suit different conditions.

Other advantageous features of the invention will be fully understood from the following description and claims when taken in connection with the accompanying drawings, forming part of this specification, in which—

Figure 1 is a side elevation of the excavator constituting the present and preferred embodiment of my invention. Fig. 2 is a top plan view of the same. Fig. 3 is an enlarged rear elevation of the machine. Fig. 4 is an enlarged detail section taken through the transverse conveyer in the direction of the width thereof and illustrating the shaft through the medium of which motion is transmitted to the belt of the transverse conveyer, and Fig. 5 is an enlarged detail section illustrating the means under the control of one of the attendants for effecting the instantaneous elevation of the shovel and its complementary conveyer. Fig. 6 is a detail perspective view illustrating the threaded shaft carried by the laterally-ad-

justable frame and the nut which is carried by the main frame and through which the threaded shaft extends. Fig. 7 is a detail perspective view showing the shaft *b'* and the sprocket-wheels *c'* and *d'* thereon.

60

Similar letters designate corresponding parts in all of the views of the drawings, referring to which—

A is the main frame of my novel excavator, which is preferably, though not essentially, 65 of steel and may be of the general construction illustrated or of any other general construction compatible with my invention without involving a departure from the scope of my invention. The said frame is supported 70 on drive-wheels *B*, which are carried by an axle *C*, journaled in suitable bearings on the frame, and the machine as a whole is propelled by an explosive-engine *D*, preferably of the horizontal four-cycle type, located on the 75 frame *A* and having its shaft *a* connected with one of the wheels *B* through the medium of a sprocket-gear *b*, fixed on said shaft, a shaft *d*, journaled in suitable bearings on frame *A* and provided with a sprocket-gear *e* and a spur- 80 pinion *f*, a sprocket-belt *g*, connecting the gears *b* and *e*, and a spur-gear *h*, fixed with respect to the said wheel *B* and intermeshed with the pinion *f*.

E are upper and lower horizontally-disposed guides, preferably T-rails, arranged on and fixed to the forward portion of the frame *A*.

F is a forward laterally-adjustable frame having boxes *k*, Fig. 1, receiving the guides *E*.

G is a caster or steering-wheel, the hanger 90 *l* of which is journaled in the forward portion of the frame *F*, so as to support the same.

H is a gear disposed horizontally and fixed on the upper end of the shank of the hanger *l*; *I*, a transversely-disposed worm-gear intermeshed with the gear *H* and carried by a shaft *m*, which is also equipped with a miter-gear *n*, and *J* is an upright shaft journaled in suitable bearings and bearing a miter-gear *p* and a hand-wheel *r*.

At a point adjacent to its forward end the frame *F* is provided with a platform *s*, and one of the attendants of the machine stands on this platform and is enabled, through the medium of the construction just described, to 105 easily steer the machine. For the purpose of enabling the said attendant to quickly and easily adjust the frame *F* and all of the parts carried thereby laterally or in the direction of the width of the machine I provide the 110

mechanism best shown in Figs. 1 and 2. This mechanism comprises a transverse threaded shaft K, journaled and held against endwise movement in suitable bearings on the rear end 5 of the frame F; a sprocket-wheel L, fixed on said shaft K; a nut M, fixed to the forward portion of the main frame A and receiving and engaging the shaft K; a transverse shaft N, journaled in suitable supports on the frame 10 F in close proximity to the platform s and bearing a hand-wheel t and a sprocket-wheel u; and a sprocket-belt v, connecting the sprocket-wheels L and u. From this it follows that when it is desired to shift the frame 15 F and its appurtenances laterally the same may be expeditiously accomplished by the operator on the platform s turning the wheel t, since when the said wheel t is turned the shaft K will be rotated through the nut M, 20 fixed to the frame A, and will carry the frame F with it.

The frame F and all of the parts carried thereby are moved laterally on the rails E, carried by the main frame, the shovel or 25 scraper R being raised and the wheel G being turned to a position at right angles to frame F to facilitate such operation when necessary.

Carried by the forward laterally-adjustable frame F is an elevating-conveyer disposed 30 longitudinally of the machine. This conveyer P is made up of a suitable frame w, pivoted at x on the rear portion of the frame F, so as to swing in a vertical plane, shafts y, journaled in the opposite end portions of the 35 frame w, and a belt z of a construction compatible with the purpose of my invention passed around the shafts y and adapted to derive motion from the uppermost of said shafts. Motion is transmitted from the engine D to 40 the upper rear shaft of the conveyer P through the medium of the driving connection shown in Figs. 1 and 2, which connection comprises a sprocket-wheel d', fixed on the shaft d; a transverse shaft b', journaled in the forward 45 portion of the main frame A and bearing sprocket-wheels c' and d'; a sprocket-belt e', connecting the sprocket-wheels a' and c'; a short transverse shaft f', arranged coincident with the center of movement of the elevating- 50 conveyer P and bearing sprocket-wheels g' and h'; a sprocket-belt k', connecting the sprocket-wheel d' and the sprocket-wheel g', and a sprocket-belt l', connecting the sprocket-wheel h' and a sprocket-wheel m' on the before-mentioned upper shaft y.

By reason of the arrangement of the parts of the driving connection just described it will be noticed that motion will be transmitted to the belt of the conveyer P without 60 in any manner interfering with the vertically-swinging movements or adjustment of the said conveyer.

At its lower end the frame w of the conveyer P is provided with a carrier Q, of steel 65 or other suitable metal, and to this carrier is

attached the shovel or scraper R, which by preference has its forward edge tapered back to one side of the machine, as shown in Fig. 2. As clearly illustrated in the said figure, the shovel R has side flanges p', which are disposed at opposite sides of the carrier Q and are connected to said carrier through the medium of transverse pins S, of wood or other material that is adapted to break when subjected to strain slightly greater than that to 70 which the shovel R is subjected in performing its ordinary function. By virtue of this construction it will be seen that in the event of the shovel bringing up against a stone or other fixed obstruction the connection between the shovel and the carrier will be broken and the shovel will be permitted to move rearwardly, while the carrier will ride over the obstruction, and thereby avoiding 75 wrecking of the machine. 80

For the purpose of adjusting and adjustably fixing the forward portion of the conveyer P, so as to determine the depth of the cut to be made by the shovel R, I provide the mechanism best shown in Figs. 1 and 5. This mechanism comprises a rod T, pivoted to the carrier Q and extending upwardly and forwardly through the platform s; a box U, connected to the frame F, preferably in an adjustable manner, as shown in Fig. 5; an abutment V, arranged in said box and fixed with respect to the rod T; a coiled spring W, contained in the box and interposed between the lower end thereof and the abutment V; an upright X, rising from the platform and having 90 an opening in its top for the passage of the upper threaded portion of the rod T and also having a lateral guideway r' intersecting the said opening; a hand-wheel Y, mounted on the threaded portion of the rod T and bearing against the upper end of the support X and having a circumferentially-grooved hub s' disposed in the opening of the support; a trigger t', arranged in the guideway r' of the support and adapted to enter the circumferential groove in the hub s', and a bell-crank pedal-lever u', mounted on the platform s and connected to the trigger t'. By turning the hand-wheel Y the attendant on the platform s is obviously enabled to raise or lower 100 the carrier Q and determine the cut to be made by the shovel R. It will be noticed, however, that when the rod T is moved downwardly the spring W will be compressed or placed under tension, and from this it follows 105 that when the trigger t' is disengaged from the hub of the hand-wheel Y, as by the attendant on the platform s pressing downwardly on the lower arm of the pedal-lever u', the spring W will operate to instantaneously 110 move the rod T upwardly and with it the shovel R and the lower forward portion of the conveyer P as a whole. This provision enables the attendant on the platform s to so position the lower forward portion of the con- 115 120 125 130

veyer P when he sees a stump or other large obstruction in the path of the machine that the said lower portion of the conveyer will pass over and clear the stump, and thereby avoid damage to the conveyer or any other part of the machine.

In order to relieve the pivotal connection between the conveyer P and the frame F of the thrust imposed on the shovel R, I provide 10 knee-braces Z, disposed at opposite sides of the conveyer P, one of the said braces being clearly shown in Fig. 1. The said knee-braces are fixed to and depend from the lower portion of the frame F, and their forward portions 15 are arranged back of shoulders or abutments A' on the frame of the conveyer, whereby it will be seen that the said knee-braces will take the thrust from the conveyer P and yet will not interfere in any measure with the 20 before-described vertical adjustment of the conveyer.

In the practical operation of my novel machine the dirt will be taken from the ground in an unbroken mass and will be kept in such 25 state until it is discharged from the upper end of the conveyer P, as is desirable.

B', Figs. 1, 2, and 3, is the transverse conveyer of the machine, which transverse conveyer is carried by the main frame A and is 30 designed to receive earth from the conveyer P and discharge the same into carts positioned at either side of the said main frame A and moving along with the machine. The said conveyer B' comprises a shaft a², Figs. 1 and 35 4, disposed longitudinally of the machine as a whole and bearing sprocket-wheels b² and a miter-gear c², the latter being disposed at the rear end of the shaft, (as shown in Fig. 3;) a frame d², having longitudinal slots e² receiving the shaft a²; clamps f², adjustably fixing the frame d² to uprights of the main frame A; shafts g², mounted at opposite ends of the frame d² and equipped with sprocket-wheels and a belt made up of canvas or other suitable material h²; chains i², Fig. 4, connected to the canvas and passed over the sprocket-wheels on shafts g² and arranged in engagement with and adapted to derive motion from the sprocket-wheels b² on the shaft a². When 40 desired, the said conveyer B' may also comprise suitable idler-rollers j², the purpose of which is to support and prevent undue sagging of the lower stretch of the belt. By virtue of the slots e² in the conveyer-frame d², receiving the shaft a², it will be observed that the conveyer B' may be adjusted endwise, so as to extend to the extent desired beyond either side of the main frame A. It will also be observed that the conveyer B' may be 45 50 55 60 65 70 75 80 85 90 95 100 105 110 115 120 125 130 135 140 145 150 155 160 165 170 175 180 185 190 195 200 205 210 215 220 225 230 235 A, at the rear thereof, has to do with the control of the engine and also with the direction in which the belt of the conveyer B' is caused to travel. When the machine is propelled forwardly as stated, the belt of the elevating-conveyer will receive the excavated earth from the shovel R and will carry the same in an unbroken mass upwardly and rearwardly and discharge it on the belt of the transverse conveyer B'. This latter will carry the dirt upwardly to one side of the machine and at such point will discharge the same into a cart or the like moved along with the machine at the side thereof.

I have entered into a detailed description of the construction and relative arrangement of the parts embraced in the present and preferred embodiment of my invention in order to impart a definite understanding of the said embodiment. I do not desire, however, to be understood as confining myself to such specific construction and relative arrangement of parts, as such changes and modifications may be made in practice as fairly fall within the scope of my invention as claimed.

Having described my invention, what I claim, and desire to secure by Letters Patent, is—

1. In an excavator, the combination of a wheel-supported main frame, a forward frame connected to and adjustable laterally on the main frame, a shovel and an elevating-conveyer carried by said forward frame, and means for adjusting the forward frame laterally on the main frame.

2. In an excavator, the combination of a wheel-supported main frame, a forward frame connected to and adjustable laterally on the main frame, a shovel and an elevating-conveyer carried by the forward frame, a steering-wheel supporting the forward portion of the forward frame, means for positioning the said steering-wheel, and means for adjusting the forward frame laterally on the main frame.

3. In an excavator, the combination of a wheel-supported main frame, a forward frame connected to and adjustable laterally on the main frame, a shovel and an elevating-conveyer carried by said forward frame, a nut fixed on the main frame, and a transverse threaded shaft journaled and held against endwise movement in bearings on the forward frame and extending through and engaging the nut on the main frame.

4. In an excavator, the combination of a wheel-supported main frame having upper and lower horizontally-disposed guide-rails on its forward portion, a laterally-adjustable forward frame having boxes on its rear portion receiving the said rails, a shovel and an elevating-conveyer carried by said forward frame, and coacting means on the main frame and the forward frame for adjusting the latter sidewise.

5. In an excavator, the combination of a

wheel-supported main frame having upper and lower horizontally-disposed guide-rails on its forward portion, and also having a nut provided with a transverse threaded aperture, a laterally-adjustable forward frame having boxes on its rear portion receiving the guide-rails of the main frame, a shovel and an elevating-conveyer carried by said forward frame, a transverse, threaded shaft journaled and held against endwise movement in bearings on the forward frame and extending through and engaging the nut on the main frame, a steering-wheel supporting the forward portion of the forward frame, means for positioning the said steering-wheel, means arranged adjacent to the said steering means for moving the forward frame sidewise, and a driving connection intermediate the last-mentioned means and the threaded shaft for rotating the latter.

6. In an excavator, the combination of a wheel-supported main frame, a forward frame equipped with excavating means and carried by and adjustable laterally on the main frame, and means for moving the forward frame sideways with respect to the main frame.

7. In an excavator, the combination of a wheel-supported main frame, a wheel-supported forward frame equipped with excavating means, horizontal guides connecting the main frame and the forward frame so as to adapt the latter to be adjusted in the direction of the width of the machine, and means for so adjusting the forward frame on the main frame.

8. In an excavator, the combination of a wheel-supported frame, vertically-movable excavating means carried by said frame, means for adjusting the active end of said excavating means vertically with respect to the frame, a spring arranged to be placed under tension when said end of the excavating means is moved downwardly, and means for releasing the adjusting means so as to enable the expansion of the spring to instantaneously raise the active end of the excavating means.

9. In an excavator, the combination of a wheel-supported frame, vertically-movable excavating means carried by said frame, a shaft connected to the excavating means and provided with an upper threaded portion, a nut mounted on and engaging said shaft, a trigger for normally holding said nut against movement with respect to the frame, a spring interposed between the shaft and the frame and arranged to be put under tension by downward movement of the shaft, and suitable means for disengaging the trigger from the nut.

10. In an excavator, the combination of a wheel-supported frame, vertically-movable excavating means carried by said frame, a box fixed with respect to the frame and receiving a shaft or rod, the said shaft or rod connected to the excavating means and having an upper

threaded portion and also having an abutment, a spring contained in the box and interposed between the same and the abutment of the shaft or rod, a support on the frame having an opening in its top and a guideway intersecting said opening, a nut disposed in the opening of the support and on the threaded portion of the shaft or rod and having a circumferential groove, a trigger extending through the guideway of the support and normally resting in the groove of the nut, and a pedal-lever connected to the trigger.

11. In an excavator, the combination of a frame, vertically-movable excavating means carried by said frame, means connecting the active end of the excavating means and the frame and arranged to adjust said active end of the excavating means with respect to the frame, a spring arranged to be placed under tension incident to downward movement of the said connection, and means for releasing the connection from the frame so as to enable the expansion of the spring to raise the active end of the excavating means.

12. In an excavator, the combination of a frame, excavating means comprising a shovel and an elevating-conveyer carried by said frame; the conveyer being pivoted to and arranged to swing vertically on the frame, a knee-brace connected to the frame, and an abutment on the conveyer arranged to bear against the forward portion of the knee-brace and thereby impose on the knee-brace the thrust to which the shovel is subjected.

13. In an excavator, the combination of a wheel-supported main frame, a forward frame connected to and adjustable laterally on the main frame and provided adjacent to its forward end with a platform, a shovel and an elevating-conveyer carried by the forward frame, a steering-wheel supporting the forward portion of the forward frame, means adjacent to the said platform for positioning the said steering-wheel, a nut fixed on the main frame, a transverse threaded shaft journaled and held against endwise movement in bearings on the forward frame and extending through and engaging the nut on the main frame, a shaft mounted on the forward frame at a point adjacent to the platform thereof, and a driving connection intermediate said shaft and the threaded shaft.

14. In an excavator, the combination of a carrier, a shovel having side flanges disposed alongside the carrier, and transverse pins, of wood or other readily-breakable material, extending through and connecting the flanges of the shovel and the carrier.

15. In an excavator, the combination of a main frame, wheels supporting the same, a forward frame connected to and adjustable laterally on the main frame, means for adjusting the forward frame laterally, a steering-wheel carried by and supporting the forward frame, an endless conveyer and a shovel carried by the forward frame, a transverse conveyer carried by the main frame and arranged to receive from the first-mentioned conveyer; said transverse conveyer being adjustable vertically and in the direction of its length on the main frame, an engine on the main frame, and driving connections intermediate the engine and one of the supporting-wheels of the main frame, the first-mentioned conveyer, and the transverse conveyer; the connection to the transverse conveyer being reversible.

16. In an excavator, the combination of a frame, an endwise-movable and vertically-adjustable conveyer carried by the frame and comprising a belt, means for driving the belt, and a connection intermediate the driving means and the belt comprising a reversing-gear.

17. In an excavator, the combination of a frame, an endwise-movable and vertically-adjustable conveyer comprising a shaft journaled on the frame, and a conveyer having a frame provided with slots receiving the shaft and a belt arranged in engagement with sprocket-wheels on said shaft, means for driving the shaft, a connection intermediate the driving means and the shaft including a reversing-gear, and means for adjustably fixing the frame and the belt of the conveyer with respect to the first-mentioned frame.

In testimony whereof I have hereunto set my hand in presence of two subscribing witnesses.

ARTHUR A. BOOTH.
